Primary Examiner — Elizabeth J Oswecki

(57) **CLAIM**

The ornamental design for a time capsule tube, as shown and described.

DESCRIPTION

FIG. 1 is a top front perspective view of a time capsule tube, showing my new design;

FIG. 2 is a front elevation view thereof;

FIG. 3 is a rear elevation view thereof;

FIG. 4 is a bottom plan view thereof;

FIG. 5 is a top plan view thereof;

FIG. 6 is a left side elevation view thereof; and,

FIG. 7 is a right side elevation view thereof.

The broken lines shown in the drawings depict an end cap that forms no part of the claimed design.

1 Claim, 3 Drawing Sheets
